METHOD OF MAKING SHOES.

Application filed November 11, 1926. Serial No. 147,801.

In the manufacture of McKay sewed shoes, the usual method has been to secure a rounded inner sole in position on the last bottom, then last the upper thereon and then secure 5 a metal shank stiffener to the shank before the outer sole is placed in position, the stiffener being secured by tacks which are driven therethru and clenched against the metal bottom on the last. When the shoe is 10 to carry a wood heel it is customary to provide a leather board reinforcing piece for the heel part of the inner sole, and usually this is extended to the front end of the shank, as it may be terminated at this point, by 15 skiving the front edge, without causing a ridge on the sole bottom. This reinforcing piece is usually secured to the innersole blank and both are died out together.

This method, while satisfactory under 20 some conditions, has been found to be unsatisfactory under other conditions, more particularly in the manufacture of women's shoes which have a narrow shank and usually carry a high heel, for several reasons: When 25 a shoe having a narrow shank is lasted, the edge portions of the upper and lining will frequently be drawn in onto the middle portion of the shank, at the narrower portions thereof, so that the opposite edges of the 30 upper either abut or lie close together, and when the shank is very narrow they often overlap. Under these conditions, when the metal stiffener strip is secured in position it is likely to bear at its middle portion on 35 the lasted-in edge-portions of the upper, or to bear thereon at one edge, and not at the other, or to bear on a double thickness of the upper. If, therefore, the shank stiffener strip has been shaped longitudinally to cor- 40 respond to the longitudinal curvature of the last, it is likely to be prevented, by the lasted-in upper edge portions, from having a firm bearing throughout its entire length. That is, while it may have a firm support at 45 one end and at the middle, the other end may be held away from the sole. If the strip is bent so that both ends engage the sole, then the tacks which are used to secure it are likely to be pulled out by the re- 50 siliency of the metal.

A shoe having a stiff, inflexible shank, which is rigid with relation to the heel, is very desirable and, to this end, metal shank stiffening strips have been die shaped in

transversely concave-convex form and shaped 55 longitudinally to correspond to the longitudinal curvature of the shank portion of the last on which the shoe is to be made, and then tempered, so as to secure the maximum strength and rigidly for the weight, but, 60 when it is attempted to secure such a stiffener to a shank which is so narrow that the edge portions of the upper extend beneath the stiffener to a greater or less extent according to conditions, it has been found impractical to use such a stiffener for the 65 reason that it cannot be conformed to the varying conditions above referred to. For these reasons it has been considered necessary to employ a metal shank stiffener which 70 is somewhat pliable so that it may be conformed to the varying conditions above referred to. The use, however, of such a stiffener is objectionable as, in addition to the fact that the shank of the shoe is not 75 held with the desired rigidity, any substantial change in the longitudinal curvature of the stiffener is likely to throw the heel, when attached, out of tread with the forepart, thereby causing a defect which is highly objectionable and such stiffeners are likely to 80 become disconnected from the innersole and to become misplaced as before explained.

Moreover, the use of tacks, for the purpose 85 of securing the metal stiffener in position, or of similar securing means, which must be driven through the sole and clenched against the iron bottom of the last, is objectionable for many reasons, principally be- 90 cause such means is insecure, so that the strip is liable to become disconnected from the innersole and then become misplaced, and all nails or tacks which are clenched at the inner side of the shoe are objectionable for 95 well known reasons.

The above difficulties, due to variations in the surfaces to which the metal shank strips are attached, are further increased by variations in the position in which the leather board reinforcing piece, when used, is at- 100 tached to the inner sole, that is, the skived front edge of the shank piece should, and is intended to terminate at the transverse line in which the shank and forepart sur- 105 faces of the last bottom meet, and if this piece is set too far forward, or too far back, the shank strip will not conform thereto, with the result that the strip when attached

will be supported either too high or too low at its front end.

Another difficulty which has been encountered, and is incidental to the method above referred to, results in a lateral displacement of the innersole at the shank by the lasting operation. That is, in the manufacture of McKay sewed shoes, iron bottom lasts are employed and openings are provided in the iron bottoms at several points to permit tacks to be driven into the wood to hold the innersole in position. For various reasons these openings are usually not located at more than three points. In lasting the upper onto the shank portion of the innersole, after the laster draws the upper as tightly as he can at one side and secures it by tacks, there is considerable lateral pull by the upper on the innersole until this is counter balanced by lasting it at the other side, thus pull being particularly great in the shank on account of the fact that the sides of the last in the shank form a nearly continuous surface with the bottom. In consequence, if the innersole is of light weight material, the shank portion is liable to be laterally displaced, or pulled to one side by the upper, before the lasting at the other side can be performed, and the resulting defect is not usually detected by the laster and, if detected, is difficult to correct, but, if not corrected, results in a defective shoe.

These difficulties, while primarily encountered in the manufacture of McKay sewed shoes, may also be encountered to some extent in the manufacture of shoes made by other processes which employ an inner sole and have narrow shank portions, which will enable the use of metal shank stiffeners which are molded to conform to the particular lasts on which the shoes are to be made and are transversely curved and tempered, so that they cannot be bent under any strain to which they would ordinarily be subjected, and will enable shoes, having the heels set so that they tread perfectly with the forepart, to be produced. Also to provide a method whereby the use of tacks, or similar means, for securing the metal shank stiffener to the innersole may be avoided and attachment thereof will be enabled in a manner to prevent subsequent displacement under practically all conditions and which will also prevent lateral displacement of the shank portion during the lasting operation.

I accomplish these objects, primarily, by securely attaching a rigid practically unyieldable, metal stiffener, which has been shaped to correspond to the longitudinal contour of the particular last on which the shoe is to be made, to an innersole which has been shaped to the last bottom, and to which a heel and shank reinforcing piece

has been attached in predetermined relation, then securing the parts thus connected to the last bottom in conforming position, then lasting the shoe and proceeding by the usual methods.

For a more detailed explanation of the invention, reference is made to the following specification in connection with the accompanying drawings, in which:

Fig. 1 is a plan view of an innersole with a shank reinforcing piece thereon previous to the dying out operation.

Fig. 2 is a perspective view of a metal shank stiffener strip which is preferably employed.

Fig. 3 is an edge view of the innersole after it has been died-out.

Fig. 4 is a perspective view of a last with an innersole secured thereto, and previous to lasting.

Fig. 5 is a similar view after lasting.

Fig. 6 is a longitudinal section of the finished shoe.

In the manufacture of McKay sewed shoes it is customary to provide an innersole blank, as *a*, which has not been rounded, and to attach a leather board reinforcing piece, as *b*, in position thereon, the latter being adapted to extend over all the heel and shank portion of the sole and having a skived front edge *b'*. Those parts, as thus arranged, are then died out in sole form.

In constructing a shoe according to my method, it is an essential to the success thereof that the dying out operation be so performed that the front edge *b'*, of the stiffener piece, shall in each instance be located in such a position that, when the innersole is placed in position on the last bottom with its edges in coincidence therewith, the front edge of the stiffener piece will terminate in the line in which the shank and forepart surfaces meet. In a last for a shoe carrying a high heel, these surfaces meet at a well defined angle, so that the line which marks the vertex of this angle is definitely placed. The blank from which the innersole is died out is usually somewhat longer than the die pattern, so that unless some means is provided for guiding the sole cutter, the sole is likely to be died out in such a manner that the above described relation will not be secured when the innersole is placed in position on the last. To this end the point is first ascertained where this line meets the cutting edge of the die which is used to cut out the sole and this point is, in practice, indicated on the side of the die by a mark, as indicated at *X* in Fig. 1, and when the die is placed on the blank, it is set in such a position that its indicating line *X* is directly over the edge *b'* of the reinforcing piece.

A metal shank stiffener strip *c* is provided, which is die shaped and tempered in

transversely concave-convex form, so that it is practically inflexible, and is also curved longitudinally to correspond to the curvature of the shank portion of the last on which the shoe is to be made, the end portions of the strip being flattened, so that, when in position in the shoe, said end portions will lie flat against the heel seat and ball portions of the shoe respectively.

10 In performing the next step of the method the strip *c* is placed in the middle of the shank portion of the reinforcing piece and innersole, with the convex side out and in such a position that its flattened front end 15 extends for a short distance beyond the front edge *b'* of piece *b*. The parts *a* and *b* are bent to conform to the strip *c* and are firmly secured thereto in this position by rivets *d*, which are driven through the innersole, 20 from its inner side and through piece *b* and also the strip *c* adjacent its ends and clenched against the latter, so that these parts are securely bound together, the smooth heads of the rivets being flush with 25 the inner surface of the sole, so that all possibility that the securing means for the shank stiffener will subsequently be objectionable to the wearer of the shoe is avoided.

The innersole, with the piece *b* and strip *c* thereon, is then placed in position on the last bottom and, assuming that the parts have been correctly formed and assembled, the surface of the sole which has been conformed to the stiffener strip will conform to 35 the shank part of the last when its edges coincide with the edges of the last. The innersole is then secured in this position in the usual manner by tacks *e* which are usually driven into the last at three points, two of 40 which are closely adjacent the ends of the strips *c*. With the parts thus arranged a uniform support will be provided for the strip *c* throughout its entire length and it will be securely held in this position.

45 From this point the usual operations of lasting, placing the outersole in position and sewing are performed. If the shank of the shoe is so narrow, or the upper is so full that the edge-portion of the upper over-laps the middle portion of the stiffener strip, this portion will preferably be trimmed off, so that, when the outersole is placed in position, its middle portion along the shank will directly engage the stiffener strip throughout the entire length of the latter.

55 By means of the above described method, the stiffener strip is provided with a firm bearing throughout its entire length under all conditions regardless of whether the edge portions of the upper overlap the position in which the strip is located when the shoe is lasted.

Important advantages result in securing the stiffener strip to the innersole before the latter is attached, as this enables the use of

a flat headed rivet, the head of which may be located at the inner surface of the innersole, while the clenching operation may be performed by a machine against the metal strip, so that there is practically no possibility that the strip may become misplaced as is the case when the strip is attached by a tack which is clenched against the inner surface of the sole.

As the strip *c* is held in close engagement 75 with the surface of the reinforcing piece which is in turn secured, usually by staples, to the innersole and as the latter is secured to the last close to the ends of the strip, the innersole will be pressed firmly against the 80 last and held against lateral displacement by the strip, so that when the shoe is lasted in the shank, the tendency to displace the innersole laterally by the unbalanced pull of the upper thereon will be effectively resisted 85 in most instances.

The metal stiffener strip *c* is preferably extended to a point slightly in the rear of the middle of the heel seat, so that when the heel is attached, the shank part of the shoe 90 will be held in fixed relation to the heel by the strip, and as the latter will be shaped longitudinally to correspond to the contour of the last, it will hold the ball portion of the shoe in fixed relation to the tread surface of 95 the heel, so that, if the parts are correctly constructed, which is a mere matter of design, the shoe will always tread correctly and the other defects of previous methods hereinbefore referred to will be obviated. 100

I claim:

1. The method of making shoes of the type described which consists in attaching an inflexible shank-stiffener strip, which is curved longitudinally according to the longitudinal curvature of the shank-portion of the last on which the shoe is to be made, to an initially flexible innersole, in predetermined relation, so that the latter is shaped throughout its shank portion to correspond 105 to the longitudinal curvature of the strip, then positioning the innersole on the last bottom and securing the same thereto at each end of the strip, and then lasting the upper onto the innersole, and completing the 110 making operation.

2. The method of making shoes of the type described which consists in providing an initially flexible innersole and a substantially inflexible metal shank stiffener strip 120 which is curved longitudinally according to the longitudinal curvature of the shank portion of the last on which the shoe is to be made and is of substantially less width than the narrower shank portion of the inner sole, positioning the stiffener strip on the outer side of the inner sole, so that it extends from points on the heel portion to points adjacent the ball portion, driving 125 suitably headed rivets thru the inner sole 130

from its inner side and thru each end portion of the stiffener strip and clinching the end portions of the rivets against the outer side of the strip while the heads thereof are
3 engaged with the inner side of the sole, so that the sole is securely attached to the strip and conformed to the longitudinal curvature thereof, securing the sole to the last in positioned relation, lasting the upper thereon, and completing the making opera- 10
tion.

In testimony whereof, I have signed my name to this specification.

GEORGE M. RAY.

from its inner side and thru each end portion of the stiffener strip and clinching the end portions of the rivets against the outer side of the strip while the heads thereof are engaged with the inner side of the sole, so that the sole is securely attached to the strip and conformed to the longitudinal

curvature thereof, securing the sole to the last in positioned relation, lasting the upper thereon, and completing the making opera- 10

tion.

In testimony whereof, I have signed my name to this specification.

GEORGE M. RAY.
